UNITED STATES PATENT OFFICE

149,914

DESIGN FOR A BROOCH

Herbert J. A. Skipp, East Providence, R. I., assignor to Pearl-Glo Corp., Pawtucket, R. I., a corporation of Rhode Island

Application April 14, 1947, Serial No. 138,388

Term of patent 3½ years

(Cl. D45—19)

To all whom it may concern:

Be it known that I, Herbert J. A. Skipp, a citizen of the United States, residing at East Providence, in the county of Providence and State of Rhode Island, have invented a new, original, and ornamental Design for a Brooch, of which the following is a specification, reference being had to the accompanying drawing, forming part thereof.

Fig. 1 is a plan view of a brooch, showing my new design; and

Fig. 2 is a side view of the same.

I claim:

The ornamental design for a brooch, as shown.
HERBERT J. A. SKIPP.
